(No Model.)

S. A. EISELE.
TRUCK BEARING.

No. 560,486.

Patented May 19, 1896.

UNITED STATES PATENT OFFICE.

STEPHEN A. EISELE, OF SAN ANTONIO, FLORIDA.

TRUCK-BEARING.

SPECIFICATION forming part of Letters Patent No. 560,486, dated May 19, 1896.

Application filed January 25, 1896. Serial No. 576,835. (No model.)

To all whom it may concern:

Be it known that I, STEPHEN A. EISELE, a citizen of the United States, residing at San Antonio, in the county of Pasco and State of Florida, have invented certain new and useful Improvements in Truck-Bearings, of which the following is a full, clear, and exact specification, reference being had to the accompanying drawings, forming part thereof, in

10 which—

Figure 1 is a perspective of my improved bearing, its parts being detached. Fig. 2 is a front elevation showing one side in section. Fig. 3 is a section on line 3 3, Fig. 2. Fig. 4 is a section on line 4 4, Fig. 2. Fig. 5 is a detail section on line 5 5, Fig. 3.

15 My invention relates to bearings in which the truck-axles are journaled and supplied with oil.

20 The object is to provide a bearing the lower or oil-containing section of which may be readily slid out of slideways in the upper section to receive a supply of oil even though the trucks are under heavy timbers, as would be the 25 case in sawmills; also to form an inclined or wedge-like joint between the two sections of the bearing, so that when slid in the lower or oil-cup section will be raised up close to the axle.

30 A further object is to provide such a bearing in which there will be no oil-supply holes to become filled with dust and dirt and in which the oil will be better distributed.

The invention will be first described, and 35 then specifically set forth in the claims.

In the drawings, A is the upper section of the bearing, adapted to be bolted to the lower side of the truck and provided with depending flanges A' A', between the upper ends of 40 which is formed a semicircular recess A², that receives the upper section B, of Babbitt metal, which is solid or extends from end to end of the said recess. Below this recess A², I form longitudinal grooves or slideways A³ in the 45 inner faces of the flanges A', and the lower walls a³ of these recesses are inclined from their outer ends upwardly to their inner ends, while the inner ends of the recesses A³ are provided with inwardly-extending stop lugs 50 or ribs a'. The lower sliding section A⁴ of the bearing is in the form of a semicylindrical cup, which receives and holds the oil.

This oil-cup A⁴ is provided along its longitudinal edges with slides or ribs a⁴, which are inclined on their lower faces to correspond 55 with the lower walls a³ of the grooves or slideways A³. It will be seen, therefore, that as the oil-cup is slid inwardly it will be stopped by lugs a' and be raised till the upper faces of the ribs or slides fit close to the upper walls 60 of the slideways or grooves, and a tight dust-proof joint will thus be afforded. The cup is held from sliding outwardly by means of the latches C, which are pivoted to the outer end of the upper bearing-section A and swung 65 down over the outer ends of the ribs or slides a⁴. When the latches are swung up, as in dotted lines, by means of their finger-pieces c, the oil-cup may be pulled out by means of its finger-pull c', which depends from the 70 lower side of its outer end. The outer corners of the inner ends of the slides or ribs a⁴ are rabbeted, as at a⁵, to receive the stop-lugs a', above described. B' B' are semicircular pieces of Babbitt metal secured to the ends of the 75 oil-cup A⁴ and extending inwardly about one-half inch toward the center thereof to prevent the oil from spilling. These pieces of Babbitt metal also closely fit the axle and prevent the entrance of dust to the oil-cup. 80

It will be seen that the above-described bearing is very simple and inexpensive and that it may be readily supplied with oil by simply sliding the oil-cup outwardly. The oil-cup will be provided with any absorbent filling 85 to conduct the oil to the axle.

What I claim is—

1. A bearing comprising an upper section and a separable lower section, wedge-like interlocking portions being extended in the direction of length of said sections whereby they may be held together substantially as shown and described. 90

2. A bearing provided with an upper section and a longitudinally-slidable lower oil-cup section, a wedge-like slide and slideway being provided by which to connect the two sections, substantially as set forth. 95

3. A bearing comprising the upper section having depending flanges provided in their adjacent faces with longitudinal grooves having inclined walls, and a lower oil-containing section provided with longitudinal slides or ribs having inclined slides and slidable in 100

said grooves and means for holding the lower section in place, substantially as set forth.

4. A bearing comprising an upper section, having opposed longitudinal grooves the lower walls of which are inclined upwardly from their outer ends, and the lower slideable oil-cup having longitudinal ribs inclined on their

lower sides to correspond with said lower walls of the grooves, and means for holding the oil-cup in place, substantially as set forth. ¹⁰

STEPHEN A. EISELE.
